UNITED STATES PATENT OFFICE.

JOHN HIRONS, OF WELLINGTON, KANSAS, ASSIGNOR OF ONE-HALF TO
MARTIN V. B. HOLMS, OF SAME PLACE.

RAILWAY-RAIL JOINT.

SPECIFICATION forming part of Letters Patent No. 427,512, dated May 6, 1890.

Application filed January 20, 1890. Serial No. 337,444. (No model.)

To all whom it may concern:

Be it known that I, JOHN HIRONS, a citizen of the United States, residing at Wellington, in the county of Sumner and State of Kansas, 5 have invented new and useful Improvements in Railway-Rail Joints, of which the following is a specification.

My present invention relates to the construction and joining of railway-rails, and the 10 purpose thereof is to provide a removable rail-section, which is linked to the end of the rail and jointed to a similar section upon the end of the meeting rail, the structure being supported by a chair or step, whereby a solid, 15 rigid, substantial, and unyielding union is effected, having a resistance to strain equal to that afforded by the solid portions of the rail proper.

It is the purpose of my invention to provide 20 a simple and durable construction of this type, which shall admit of contraction and expansion and give a smooth passage to the wheels without jar or jolt, while the joint may at any time be renovated without removing the rail, and at a comparatively small expense.

It is my further purpose to combine with the short rail-sections connected to the main rails a supporting-chair of novel construction 30 adapted to receive the rail-foot and afford a foundation for the joint and for the ends of the main rails contiguous to the joint, the construction and arrangement being such as to permit the removal of the short rail-sections whenever they become worn or battered 35 and the substitution therefor of new and sound sections of similar form without removing or disturbing the rails.

My invention also includes the provision of 40 an improved construction of the meeting ends of the rail-sections, whereby a better, more durable, and smoother joint is formed than has heretofore been used.

The invention consists to these ends in the 45 several novel features of construction and new combination of parts hereinafter fully set forth, and then definitely pointed out in the claims following this specification.

To enable others skilled in the art to practice my said invention, I will describe the same

in detail, reference being had to the accompanying drawings, in which—

Figure 1 is a side elevation of a portion of the roadway at the joint, showing my invention. Fig. 2 is a plan view of the same. Fig. 3 is a transverse section of Fig. 2 in the line *x x*. Fig. 4 is a detail view of the end of one of the rails with the short rail-section connected thereto. Fig. 5 is a plan view of the chair.

In the said drawings, the reference-numeral 1 denotes the main rail of the roadway, which is of the usual form. To the ends of these rails are linked short rail-sections or joint-sections 2, which abut squarely against the 65 ends of the main rails and are connected thereto by means of a link-plate 3, laid flat against the webs of the abutting ends and fastened by pivot-bolts or rivets 4. At its other extremity one of these joint-sections is provided with a semicircular or concave seat 5, cut in the end of the rail-head and of such width as to leave shoulders 6 upon the edges of the rail-head. This seat receives a half-round or convex projection or head formed 70 upon the outer end of the other joint-section and fitting closely within the seat 5, shoulders 8, formed transversely to the rail and lying outside of the convex head or projection 7, abutting against the square ends or 75 shoulders 6 of the other section, by which construction the adjacent ends of the said joint-sections are interlocked by what may be termed a "tongue-and-groove" connection. The joint-sections thus interlocked or tongued 80 or grooved together and united with the main rails are supported on a chair 9 of such length as to include also a portion of the ends of the main rails. This chair is composed of a heavy 85 plate of metal having upon its longer parallel edges flanges 10, which rise from its surface, the interval between said flanges being just sufficient to admit the foot 12 of the rail, as well as that of the joint-section. In the bottom of the chair, and preferably in the central line, I form two or more openings 13, to receive bolts or spikes, which are driven into the sleepers, a countersink being provided to receive the head of the spike and form flush surfaces. In the marginal flanges 10 are 90

formed at proper intervals slots or notches 14, which may be cut entirely through or only partly through said flanges, in order to enable the heads of the spikes to make engagement with the foot of the rail and joint section.

When the parts are united in the manner set forth, fish-plates 15 are placed upon each side of the webs in the usual manner and fastened by bolts 16, which pass through bolt openings 18 in the webs, at least one of said bolts passing through the web of each joint-section, while the fish-plates are of such length as to afford engagement for one or more bolts passing through the webs of the main rails. These fish-plates underlie and afford a support to the meeting shoulders 6 and 8 at the joint and unite the joint-sections with the main rails with a strength and rigidity equal to that of the integral portions of the rail. This union, taken in connection with the support afforded by the chair, affords a joint of great strength and durability, which will give a perfectly smooth passage to the wheels without jar or jolt and without unusual sound.

The form of the joint and the method of uniting the parts preserves the rails and prevents the ends from becoming battered, splintered, and worn or beaten down; while the smooth and easy passage it gives to the wheels saves the rolling-stock from much wear and tear, besides promoting the safety of the train and enabling it to run at very high speed without danger. In repairing the road, moreover, a large economy of time, labor, and expense is effected, since the worn portions may readily be removed by simply drawing the spikes which engage the joint-sections, removing the fish-plates, and taking off said sections, which are replaced by new ones, the joint-sections being preferably duplicates one of another, although they may be of various lengths, if preferred.

What I claim is—

1. In a railway-rail joint, the combination, with the main rails, of a series of interposed short joint-sections interlocked at their adjacent ends and a series of links connecting the interlocked joint-sections with the respective main rails, substantially as described. 50

2. In a railway-rail joint, the combination, with the main rails, of short joint-sections connected to the ends of the main rails by pivotally-attached links, a chair underlying 55 and supporting said sections and the ends of the rails, and fish-plates uniting the same, substantially as shown and described.

3. In a railway-rail joint, the combination, with the main rails, of short joint-sections 60 connected to the same by pivotally-attached link-plates, a chair spiked to the sleepers and having marginal flanges confining the foot of the rail, said marginal flanges being partly or wholly cut through to permit the spikes to 65 engage the rail-foot, and fish-plates uniting the joint-sections and main rails, substantially as shown and described.

4. In a railway-rail joint, the combination, with the ends of the main rails, of short joint-sections connected thereto by pivotally-attached plates, said joint-sections being provided, respectively, with a concave seat in one and a convex head at the other, which engage to form the joint, a chair underlying the same, 75 and fish-plates uniting the joint-sections and main rails, substantially as shown and described. 70

5. In a railway-rail joint, the combination of the main rails, a series of interposed short 80 joint-sections, a series of links respectively connecting the joint-sections to the main rails, and fish-plates covering the links, substantially as described.

In testimony whereof I have affixed my signature in presence of two witnesses.

JOHN HIRONS.

R. W. HURLBUT.

Correction in Letters Patent No. 427,512.

It is hereby certified that the name of the assignee in Letters Patent No. 427,512, granted May 6, 1890, upon the application of John Hirons, Wellington, Kansas, for an improvement in "Railway-Rail Joints," was erroneously written and printed "Martin V. B. Holms," whereas said name should have been written and printed *Martin V. B. Holmes*, and that the said Letters Patent should be read with this correction therein that the same may conform to the files and records of the case in the Patent Office.

Signed, countersigned, and sealed this 3d day of June, A. D. 1890.

[SEAL.]

CYRUS BUSSEY,
Assistant Secretary of the Interior.
